Patented Nov. 28, 1922.

2 SHEETS—SHEET 1.

Inventor:
Donald W. Black,
by Edward F. Allen
his Atty.

UNITED STATES PATENT OFFICE.

DONALD W. BLACK, OF SOMERVILLE, MASSACHUSETTS.

CENTRIFUGAL PAINT MIXING OR SMOOTHING MACHINE.

Application filed April 15, 1922. Serial No. 553,237.

To all whom it may concern:

Be it known that I, DONALD W. BLACK, a citizen of the United States of America, and a resident of Somerville, in the county 5 of Middlesex and Commonwealth of Massachusetts, have invented certain new and useful Improvements in Centrifugal Paint Mixing or Smoothing Machines, of which the following is a specification.

10 This invention relates to a centrifugal paint mixing or smoothing machine wherein paint which has been previously mixed by any of the usual methods is put through a final smoothing process before it is considered to be in proper condition to apply.

15 Heretofore the final process of mixing, or as herein called smoothing process, has been a slow and time wasting operation, being done by hand until, in the judgment of the 20 mixer, the paint was in condition for a still further process of screening or straining, which was necessary before it was considered in fit condition to be used.

25 The hand process was not only a slow and inefficient one but the screening or straining operation was somewhat detrimental to the consistency of the paint and incurred unnecessary waste.

30 Necessarily paint of a certain consistency during the initial mixing thereof lost some of its body during the screening or straining process, and, too, the small unbroken particles of pigment or coloring matter which could not pass through the strainer 35 was cast aside as waste.

It is an object of the present invention to make use of an old and well known form 40 of centrifugal machine to which certain improvements have been applied which in themselves are simple, of comparatively low expense and readily applied to machines of this type already in existence and yet function perfectly for the results desired.

45 It is a further object of the invention to arrange for a continuous flow of partially mixed paint to the machine whereby the services of an attendant may to great extent be dispensed with.

Another object of the invention is to provide 50 means to thoroughly break up, mash or disintegrate the previously unbroken particles of pigment or coloring matter of the paint in such manner that a smoother product is obtained and waste greatly and in fact 55 almost wholly, eliminated. From the foregoing it will be readily seen that the inven-

tion consists of means to admit of a continuous flow of paint to the machine for the final treatment thereof and of means, aided by centrifugal action to thoroughly 60 and effectively break up any small particles of pigment or coloring matter that had defied the previous mixing process.

The invention further consists in certain 65 novel features of construction and arrangement of parts which will be fully understood from a description of the drawings and the claims hereinafter given.

Of the drawings:

Figure 1 represents in vertical section one 70 type of centrifugal machine with the improvements added thereto.

Figure 2 is a top plan of the machine partially broken away.

Figure 3 a top plan view of a fragment of 75 the disintegrating device partially broken away and shown on an enlarged scale.

Figure 4 a section on the line 4-4 Figure 3.

Figure 5 is a section similar to Figure 4 80 showing a modified form of disintegrating device.

Figure 6 a section similar to Figure 5 showing the means for holding the rigid members of the disintegrating device in 85 spaced relation.

Figure 7 is a detail to be referred to.

Like characters represent like parts throughout the several figures of the drawings.

90 Referring to the drawings:

The invention is herein shown as applied to a well known type of centrifugal machine and while previously it has been referred to in the mixing or smoothing of paint it is 95 obvious that it may be used for mixtures other than paint where similar treatment would be beneficial. The type of machine shown is commonly known as a separator and is especially efficient in separating oil 100 from metal objects such as screws or metal chips and it is conveniently adapted for use in connection with the present invention.

Briefly the machine consists of a base 10 having upstanding therefrom a column 11 105 to which the bowl 12 is secured. Within the column 11 and resting on the base 10 is a socket 13 adapted to receive and support the non-rotatable sleeve 14 which forms an elongated bearing for the container rotating 110 shaft 15. The said shaft may be driven by any usual or suitable means, as for instance

the worm 16 on the shaft 17 which in most instances is a flexible one and direct connected to a motor of one sort or another. The said worm 16 meshes with and drives the worm gear 18 fast on the shaft 15. The usual springs 19 being employed to maintain the sleeve 14 and shaft 15 yieldingly in vertical position.

Fast on the shaft 15 is a pan or container 10 support 20 upon which rests the container 21 which has the hub 22 integral therewith.

Preferably the shaft 15 is made in two parts, the upper part 23 being centrally bored with its end screw threaded in the 15 end of part 15 which is also externally threaded to receive the nut 24 which clamps the container hub between it and the support 20 whereby the container is caused to rotate with the shaft 15 and may be readily 20 removed therefrom when occasion requires.

The part 23 extends upwardly through the container cover 25 which is preferably of wood having a reinforcing plate 26 which in this instance extends beyond the edge of 25 the container for a purpose to be later explained. When the machine is in use the covers 25 and 26 will be firmly clamped to the container 12 by a plate 27 which in turn is firmly held in place by the nut 28.

The part 23 is provided with perforations 29 which communicate with the central bore 30 of said part 23 and form outlets therefrom for the passage of the paint or other mixtures it is intended shall be passed 35 through the machine.

The upper end of said part 23 is provided with a removable bell shaped mouth 31 which is adapted to receive paint from a source of supply through the funnel shaped 40 end of a pipe or conduit 32.

The conduit 32 is mounted on the bail like member 33 which is pivoted to the bowl 12 at 34 at one end thereof and its other end adapted to be secured by the bolt 35 in such 45 manner as to be swung aside to permit of the removal of the container 21 if desired.

Viewing Figure 1 it will be seen that the structure shown therein is such that a continuous flow of paint may be directed to the 50 container 21 through the funnel 32, bell mouth 31, bore 30 and out through the perforations 29 to said container where the disposal thereof will be later on referred to.

It will be observed that the covers 25 and 55 26 extend beyond the edge of the container 21, the cover 25 only slightly, while the cover 26 extends an appreciable distance beyond.

As seen in Figure 1 this arrangement 60 forms a convenient setting for the brush like annulus 40 made up preferably of four parts or quadrants which are bolted to the cover 25 by bolts 41 and are readily applied to or removed therefrom for the purpose of 65 cleansing or renewal.

For convenience of manufacture the brush like annulus is made as before stated in four parts but for the purpose of explanation it might be made as a single member and will be herein referred to as a single member. 70

The preferred form shown in Figures 1 to 4 inclusive is composed of a back board 45 to which the groups or bunches of bristles or bristle like material are secured 75 in any usual or well known manner; and an end confining board 46 to which the bristles or like material is also secured as seen in Figure 4 of the drawings.

At intervals as seen in Figures 3 and 6 80 a group of bristles is omitted and a tube 47 is inserted through which bolts 41 pass, the nuts 48 thereof being set up firmly secure the said boards in spaced relation.

Some of the said bolts extend through 85 the cover 26 to thereby secure the annulus thereto.

The container 21 has a series of ribs or vanes 50 adapted to impart and maintain circular motion to the paint when the machine is being driven. 90

At the high rate of speed at which this machine is designed to be driven it will be readily understood that the centrifugal force imparted to the paint will cause it to 95 travel up the inclined inner wall of the container and exert great pressure on the covers 25 and 26, particularly adjacent the edges thereof. This pressure is great enough to flex the covers and cause a slight 100 opening between the cover 25 and the edge of the container 21. Through this opening the paint is forced in a thin film, the pressure being so great as to carry the paint through the groups of bristles, and any unbroken particles of pigment or coloring matter carried by the paint as it passes through the bristles will be thoroughly torn asunder and disintegrated to the extent that the paint upon leaving the brush is free of 110 all lumps and particles of unbroken pigment which is not strained therefrom, but is actually broken up and carried therewith.

The brush like annulus may be made in 115 various ways and the groups or bunches of bristles may be groups of any material suitable for the purpose.

Figures 5 and 6 show a modified form of annulus which is somewhat less costly to 120 make than the preferred form shown in Figure 4. In this instance the groups of bristles are shown as secured to one of the boards 45* only, while the end confining board 46* has upstanding annular ribs 55 125 the purpose of which is to keep the groups compact and offset the tendency to bend when subjected to the pressure of the paint projected therethrough.

For the best results it is intended to use 130

the form shown in Figure 4, as the groups are individually held more compact and uniform in compactness, whereby the breaking up process is bound to be more thoroughly and evenly accomplished. Preferably the film like projection of the paint strikes the brush like annulus at a point slightly removed from the back board 40 and partly for this reason the cover 25 extends beyond the edge of the container 21 and is of slightly greater thickness than the back board 40.

This construction compels the film like stream of paint to assume an approximately horizontal plane and directs it to a point slightly below the board 40 where the density of the bristles is more uniform and best fitted for the disintegrating action on the pigment particles.

20 In Figure 3 is shown a novel device 60 to be used at the junction of two quadrants, its function being to fill the gap between the series of groups of the said quadrants so that possibility of unbroken particles passing therethrough will be eliminated.

This device is in reality a space filling partition which has a blank wall 61 facing the on-coming paint, and radially extended corrugated walls 62 adapted to partially embrace and confine adjacent groups of bristles to thereby maintain the compactness thereof and incidentally retain the device in its proper position. The said device may be otherwise secured to the boards 30 by means of tacks or screws through the upwardly and downwardly extending tabs 63.

It is not known that a machine of this class has ever been used wherein a continuous flow of liquid or semi-liquid material is passed therethrough and wherein all the material was passed through and not strained and parts thereof left therein. It is therefore the intention to claim broadly 40 a machine of this class wherein a continuous flow of material is supplied thereto, and wherein approximately all of said material is ejected from said machine during the operation thereof.

50 Having described the invention I claim:

1. In a device of the class described, a container for the material to be operated upon, adapted to be rotated at a high speed; a cover for said container normally sealing it but adapted to yield under pressure of said material in said container; means to supply material continuously to said container while in motion; and a fibrous material adjacent the mouth of said container 55 through which said material is forcibly projected from said container, so arranged and of such character as to disintegrate lumps of said material on their forced passage through said fibrous material.

2. In a device of the class described, a 65 container for the material to be operated upon adapted to be rotated at a high speed; a cover for said container normally sealing it but adapted to yield under pressure of said material in said container; means to supply material continuously to said container while in motion; and a ring of bristles adjacent the mouth of said container through which said material is projected from said container, so arranged as to disintegrate unbroken particles of material on their forced passage therethrough.

3. In a device of the class described, a container for the material to be operated upon, adapted to be rotated at high speed; 80 means to rotate said container including a shaft centrally disposed therein, a portion of said shaft being centrally bored and having outlets therefrom to said container; means to supply material to said bored shaft while in motion; and means adjacent the mouth of said container consisting of a ring of fibrous material the ends of which are held from lateral movement and between which unbroken particles of material forcibly projected from said container will be disintegrated by and carried through said means.

4. In a device of the class described, a container for the material to be operated upon adapted to be rotated at high speed; 85 a cover for said container normally sealing it but adapted to be flexed under the pressure of the said material in said container; a series of groups composing a ring of bristle like material the ends of which are held from lateral movement and between which said material is forcibly projected from said container adjacent the mouth of said container, whereby particles of material previously unbroken will be disintegrated upon 100 their passage therethrough.

5. In a device of the class described, a conical container for the material to be operated upon adapted to be rotated at a high speed; a cover for said container normally sealing it but adapted to yield under pressure of the material in said container; a disintegrating medium consisting of a ring of bristles the extreme ends of which are held from lateral movement surrounding said container adjacent the mouth thereof, said ring being composed of two circular boards spaced apart between which the said bristles are perpendicularly arranged the ends thereof being fast with said 110 boards between which the said material is forcibly projected; and means to effect a continuous flow of material to said container.

Signed by me at Boston, Mass., this 12th 125 day of April, 1922.

DONALD W. BLACK.
